Primary Examiner — Michelle E. Wilson*Assistant Examiner* — Jessie A Kwasney(74) *Attorney, Agent, or Firm* — Warner Norcross + Judd LLP(57) **CLAIM**

The ornamental design for an instrument cleaner as shown and described.

DESCRIPTION

FIG. 1 is a perspective view of an instrument cleaner embodying the new design;

FIG. 2 is a front view thereof;

FIG. 3. is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings illustrate portions of the instrument cleaner which form no part of the claimed design.
